LIQUID FUEL BURNER

Kemper P. Brace, South Bend, Ind., assignor to
 International Engineering Corp., Chicago, Ill.,
 a corporation of Illinois

Application June 29, 1938, Serial No. 216,434

2 Claims. (Cl. 158—96)

This invention relates to liquid fuel burners and more particularly to oil burners for use in heating plants.

One of the objects of the invention is to provide a liquid fuel burner which is efficient and safe in operation and at the same time extremely simple and cheap to construct. According to one desirable arrangement the burner includes no moving parts except the oil valves and their controls.

Another object of the invention is to provide a liquid fuel burner operative at either high or low rating. Preferably the burner operates constantly and changes from high to low rating under the control of a thermostat.

Another object of the invention is to provide a liquid fuel burner in which the fuel supply is shut off upon the accumulation of a predetermined amount of unburned fuel. According to one desirable arrangement fuel is supplied to the burner through a constant level float chamber whose float valve is closed after a predetermined amount of unburned fuel has accumulated.

Still another object of the invention is to provide a liquid fuel burner including a novel two position valve to control high and low operation.

Other objects and advantages of the invention including desirable sub-combinations and structural features will be apparent from the following description read in connection with the accompanying drawings, in which:

Figure 1 is a partial perspective of a furnace equipped with a burner embodying the invention;

Figure 2 is a central section through the burner;

Figure 3 is a section on the line 3—3 of Figure 2;

Figure 4 is a section with parts in elevation of the constant level chamber and fuel cut off mechanism; and

Figure 5 is a section through the fuel control valve.

Figure 1 illustrates a heating furnace 10 having its combustion space connected to a stack or other draft producing means, not shown, and formed with provisions for heating a transfer medium to conduct heat to a dwelling room or other space to be heated. The front of the furnace has a fire door 12 formed with an adjustable shutter opening 14 and has at its lower part an ash pit 16 open at its outer end.

The burner comprises a plate 18 fitting over and secured to the ash pit and having a central opening 20. A tube 22 is secured to the plate 18 in register with the opening 20 and extends

into the furnace, a partition 24 formed with a central opening being secured in the tube intermediate its ends and the inner end of the tube being lined with refractory material 26. All 5 the lower part of the central opening the partition 24 is formed with an outwardly extending flange 28 and has a plurality of brackets 30 spaced from its inner side around the central opening.

10 A burner element 32 formed of porous refractory material and having a plurality of air passages 34 therethrough is mounted in the opening in partition 24 resting on the flange 28 and held in place by the brackets 30. Preferably the flange 28 is tilted slightly to tilt the element 32 against the brackets 30 to hold it in place, it having been found that with this arrangement other support for the element is unnecessary.

Oil or other suitable liquid fuel is supplied to 20 the element 32 through a pipe 36 which extends inwardly through the plate 18 and downwardly through the tube 22 to terminate just above the burner element. The pipe 36 is connected through a manual shut-off valve 38 and a two 25 position valve 40 to a constant level fuel chamber 42 which is mounted on the front of the plate 18. Fuel is supplied to the chamber 42 through a pipe 44 from a tank or other suitable source under the control of a valve 46 controlled 30 by a float 48 (Figure 4).

The two position valve 40, as best seen in Figure 5, includes a slidably mounted rod 50 projecting through one end of the valve housing and having one end pointed to project into and 35 variable to restrict a port 52. The rod 50 carries a collar 54 and a spring 56 engages the collar and a flange in the valve body to urge the valve away from the port 52. A cap 58 is screw threaded to the end of the valve body around 40 the rod 50 and the rod carries a nut 60 outside of and engageable with the cap.

The cap 58 and nut 60 provide respectively 45 high and low adjustments to determine the high and low positions of the valve. The high adjustment is effected by screwing the cap more or less onto the body to limit outward movement of the rod 50 by engagement of collar 54 with the cap thereby to limit the maximum opening movement of the valve. The low adjustment is 50 effected by screwing the nut 60 more or less onto the rod 50 so that the nut will engage the cap 58 to limit inward closing movement of the valve.

The valve is controlled by a bimetal strip 62 55 secured at one end to an insulating bracket 64

on the float chamber 42 and with its other end engageable with the end of rod 58 or nut 60. A heating coil 66 is wound around the strip 62 connected at one end to the strip and at its other end to a wire 68. As shown the strip 62 is grounded through the chamber 42 but it will be understood that a two wire system could be used instead of grounding one wire if desired.

The wire 68 is connected, as best seen in Figure 1, to one side of a grounded transformer 10 through a conventional room thermostat 12. When the room temperature drops below a predetermined degree the thermostat closes and when it is above a predetermined degree the thermostat opens.

In operation the float chamber is connected to a suitable oil supply and the manual valve 38 is opened so that oil will flow through pipe 36 to the element 32. The burner may now be lighted by touching a match or the like to the element 32, the stack draft drawing air through the openings 34 to vaporize oil and the mixture of air and oil burning in the tube 22 and in the combustion space of the furnace.

If the room temperature is above the value for which thermostat 12 is set it will be open and the heating coil 66 will be de-energized. At this time the strip 62 is cool and deflects downwardly to press the valve 50 to the low position as shown in Figure 5 in which the flow of oil is restricted. In this position not enough oil will be supplied to saturate the entire element 32 and the flame will burn over only a portion of its area to provide low rating operation.

Should the room temperature drop to a value below that for which thermostat 12 is set the coil 66 will be energized to heat strip 62 and cause it to deflect upwardly. Valve rod 50 will be raised by spring 56 to open port 52 further and increase the supply of oil so that a greater area of element 32 will be saturated and the flame will be increased. Preferably the high and low operations are adjusted through cap 58 and nut 60 so that the low rating is slightly less than the normal demand and the high rating is slightly greater. Thus by alternating between high and low rating under the influence of the thermostat the room temperature is kept at the desired value.

In the event of flame failure for any reason it is desirable to shut off the flow of oil until the burner has been relighted. According to the present invention this is accomplished by connecting a pipe 74 to the tube 22 just in front of the partition 24 to carry off any unburned oil dripping from the element 32 or collecting in the tube 22. The pipe 74 extends through the plate

18 to discharge into a receptacle 76 which is secured at one side to a rod 78 journaled in brackets 80 on the front of the plate. The rod 78 has a right angular extension 82 connected by a link 84 to one end of a lever 86 which is pivoted at its other end on the top of the chamber 42. A pin 88 is connected to the lever 86 and extends through the top of chamber 42 in register with the float valve 46, a spring 90 urging the lever upwardly and normally balancing the weight of the receptacle 76.

Normally the spring 90 holds the pin 88 out of engagement with the float valve so that the float valve opens and closes under the sole control of the float 48. After a predetermined quantity of oil has accumulated in the receptacle 76 its weight will be sufficient to overcome the spring 90 and press the rod 78 against the valve 46 to hold it closed regardless of the action of the float. Thus the oil supply will be cut off until the reservoir 16 has been emptied and the burner relighted.

While one embodiment of the invention has been shown and described in detail it will be understood that many changes might be made therein and it is not intended to limit the scope of the invention to the exact form shown nor otherwise than by the terms of the appended claims.

What is claimed is:

- 30 1. A liquid fuel burner comprising a burner tube adapted to extend into the combustion chamber of a furnace, a partition in said tube having an opening therein, a porous element fitting in said opening and formed with air passages therethrough, a supporting bracket on one side of the partition on which said element rests, brackets on the other side of the partition engaging the surface of said element to hold it in place, and means to supply liquid fuel to said element.
- 35 2. A liquid fuel burner comprising a supporting plate having an opening therein, a burner tube secured to the plate in register with the opening and projecting from one side of the plate, a porous element in said tube formed with air passages therethrough, a constant level chamber secured to the other side of the plate and having a float-controlled valve therein, a conduit extending from said chamber to a point adjacent the porous element to supply fuel to the porous element, a container movably mounted below the constant level chamber on said other side of the plate, a conduit to conduct unvaporized fuel from the porous element to said container, and linkage operated by movement of the container in response to a predetermined weight of fuel therein to close said float-controlled valve.
- 40 3. A liquid fuel burner comprising a supporting plate having an opening therein, a burner tube secured to the plate in register with the opening and projecting from one side of the plate, a porous element in said tube formed with air passages therethrough, a constant level chamber secured to the other side of the plate and having a float-controlled valve therein, a conduit extending from said chamber to a point adjacent the porous element to supply fuel to the porous element, a container movably mounted below the constant level chamber on said other side of the plate, a conduit to conduct unvaporized fuel from the porous element to said container, and linkage operated by movement of the container in response to a predetermined weight of fuel therein to close said float-controlled valve.
- 45 4. A liquid fuel burner comprising a supporting plate having an opening therein, a burner tube secured to the plate in register with the opening and projecting from one side of the plate, a porous element in said tube formed with air passages therethrough, a constant level chamber secured to the other side of the plate and having a float-controlled valve therein, a conduit extending from said chamber to a point adjacent the porous element to supply fuel to the porous element, a container movably mounted below the constant level chamber on said other side of the plate, a conduit to conduct unvaporized fuel from the porous element to said container, and linkage operated by movement of the container in response to a predetermined weight of fuel therein to close said float-controlled valve.
- 50 5. A liquid fuel burner comprising a supporting plate having an opening therein, a burner tube secured to the plate in register with the opening and projecting from one side of the plate, a porous element in said tube formed with air passages therethrough, a constant level chamber secured to the other side of the plate and having a float-controlled valve therein, a conduit extending from said chamber to a point adjacent the porous element to supply fuel to the porous element, a container movably mounted below the constant level chamber on said other side of the plate, a conduit to conduct unvaporized fuel from the porous element to said container, and linkage operated by movement of the container in response to a predetermined weight of fuel therein to close said float-controlled valve.
- 55 6. A liquid fuel burner comprising a supporting plate having an opening therein, a burner tube secured to the plate in register with the opening and projecting from one side of the plate, a porous element in said tube formed with air passages therethrough, a constant level chamber secured to the other side of the plate and having a float-controlled valve therein, a conduit extending from said chamber to a point adjacent the porous element to supply fuel to the porous element, a container movably mounted below the constant level chamber on said other side of the plate, a conduit to conduct unvaporized fuel from the porous element to said container, and linkage operated by movement of the container in response to a predetermined weight of fuel therein to close said float-controlled valve.
